CRUSHING MILL CONCAVE HOLDING MEANS

Filed Oct. 9, 1928

UNITED STATES PATENT OFFICE

HARVEY H. RUMPEL, OF MILWAUKEE, WISCONSIN, ASSIGNOR TO SMITH ENGINEERING WORKS, OF MILWAUKEE, WISCONSIN, A CORPORATION OF WISCONSIN

CRUSHING MILL CONCAVE HOLDING MEANS

Application filed October 9, 1928. Serial No. 311,346.

This invention relates to improvements in crushing mill concave holding means.

It is one of the objects of the present invention to provide a crushing mill concave holding means in which the concave member is connected to its support in a manner to firmly hold the concave member in position and to permit its easy removal in case of breakage or repair.

10 A further object of the invention is to provide a crushing mill concave member having means for yieldingly holding the concave member in working position.

15 A further object of the invention is to provide a crushing mill concave holding means which is of simple construction, is strong and durable, and is well adapted for the purpose described.

20 With the above and other objects in view the invention consists of the improved crushing mill concave holding means and its parts and combinations as set forth in the claims, and all equivalents thereof.

25 In the accompanying drawing in which the same reference characters indicate the same parts in all of the views:

Fig. 1 is a vertical central sectional view of the upper portion of a crushing mill provided with the improved concave holding 30 means;

Fig. 2 is a transverse sectional detail view thereof taken on line 2—2 of Fig. 1; and

Fig. 3 is a top view of the concave grinding member removed from the mill.

35 Referring to the drawing, the reference numeral 5 indicates a lower frame or casing which is of cylindrical form and is provided with an upper and outwardly extending flange 6. A crusher shaft 8 eccentrically 40 journaled in a sleeve shaft 9 is provided with a crusher head 10 at its upper end. A cap 11 holds the head in position on the shaft 8.

An upper housing or frame 12 is formed 45 with an annular rounded flange 13 which extends over and engages the upper rounded flange 6 of the main frame. Bolts 14 extend downwardly through both flanges 6 and 13 and are encircled by coiled springs 15 which yieldingly hold the upper housing in position. Pins 16 and springs 15' also assist in

holding the curved portions of the frame members in position.

The upper portion of the housing is split radially on its opposite sides as indicated by the numeral 17 to permit a slight give of said parts, and transverse bolts 18 extend through radial lugs 18' formed on the split portions to draw the two parts into clamping engagement with the upper or concave frame member 19 around which it extends. The portion 60 of the concave member surrounded by the housing is of cylindrical form, and is provided with an inwardly extending annular flange 20 for receiving segmental shims 21 which are placed at spaced intervals around 65 the flange and between the flange and the housing to adjust the height of the concave member with relation to the crusher head 10. Bolts 22 adjustably support the weight of the concave frame member 19, and pins 23 70 serve as guides to hold the parts in engagement. Said bolts and pins are positioned in the space between the end portions of the shims.

An outer or concave crushing member 24 75 surrounds the crusher head 10 in spaced relation and is secured to the inner concave portion 19' of the concave frame member 19 by bolts 25 which pass through openings or slots in radial lugs 26 formed on the outer side of 80 the concave crushing member 24, to permit replacement of said crushing member when worn. The lugs 26 extend into recesses 27 formed in the concave member portion 19'. The contacting face portions of the parts 19' 85 and 24 are ground or machined to space the lugs 26 from the walls of the recesses, and said spaces are filled with flat pieces of wood 28 or other easily compressible material, as wood, to permit drawing the bolts tight in the event 90 that the zinc packing material 29, which is poured between the concave member and the frame while in a molten state, should give way.

The lower portion of the concave member 95 19 is provided with an apron 30 having a yielding packing ring 31 mounted on its outer side which bears against the inner wall of the casing 5 to slidably seal the connection therebetween. The upper inner portion of 100

the concave flange member 20 is provided with an upstanding collar 32 against which the inner upper edges of the concave housing bear.

5 A cylindrical support and feed spout 33 is connected to the upper portion of the concave frame member 19 and the collar 32 and extends upwardly therefrom to direct the material into the space between the concave 24 and the crusher head 10. All spaces between 10 parts where dust or crushed material may gather are filled with zinc rubber or other packing material 34 to protect said parts.

15 As the concave crushing member is completely backed and reinforced by the concave frame member, a comparatively thin concave member may be used. Furthermore, the bolted suspension of the concave member permits easy removal and replacement of the concave 20 member when worn. And still further the yielding connection between the concave frame member and the lower frame eliminates undue strain being borne by the concave member. The extension of the lugs of the 25 concave member into the recesses holds the concave members in position and relieves the holding bolts of any turning strain which might be present.

30 From the foregoing description it will be seen that the crushing mill concave holding means is of very simple construction and is well adapted for the purpose described.

What I claim as my invention is:

1. In a crusher mill having a gyratory 35 crusher head, a concave holding means therefor, comprising a support extending around the crusher head and having a concave portion provided with recesses and openings, a concave crushing member extending around 40 the head and intimately engaging the support and having projecting portions which extend into the recesses and adjacent the openings, and bolts connected to the projecting portions and extending through the openings for 45 firmly attaching the concave member to the support, the extension of the lugs relieving the bolts of rotary strain of the concave member.

50 2. A crusher, comprising a frame having a concave portion provided with recesses and openings in its side portions, a gyratory crusher head extending into the concave portion, a concave crushing member extending around the head and engaging the concave 55 portion of the frame and having outwardly projecting lugs which extend into the recesses and adjacent the side openings, and bolts extending through the lugs and the openings for firmly attaching the concave member to the frame, the extension of the lugs into the recesses relieving the bolts of rotary strain 60 of the concave member.

65 3. A crusher, comprising a frame having a concave portion provided with recesses in its sides which have openings extending there-

through, a gyratory crusher head extending into the concave portion, a concave crushing member extending around the crusher head and engaging the concave portion of the frame and having horizontally projecting lugs 70 which extend into the recesses, said lugs having openings which are in register with the openings of the frame, and bolts extending vertically through the openings of the lugs and the recessed portions of the frame for 75 firmly attaching the concave member to the concave portion of the supporting frame, said lugs relieving the bolts of rotary strain of the concave member.

4. A crusher, comprising a frame having 80 a concave portion provided with recesses in its sides which have openings extending therethrough, a gyratory crusher head extending into the concave portion, a concave crushing member extending around the crusher head 85 and having outwardly projecting lugs which extend into the recesses, said lugs having openings which are in register with the openings of the frame, pieces of yielding material interposed between the lugs and the lower surfaces of the recessed portions of the frame, and bolts extending through the openings of the lugs and the recessed portions and through the interposed pieces of material for attaching the concave member to the concave portion 90 of the supporting frame.

5. A crusher, comprising a lower frame having an upper rounded edge, an upper frame having an annular groove in its lower edge portion into which the rounded edge 100 of the lower frame extends, means yieldingly holding the two frames together, an inner frame extending into the upper frame and having a concave inner portion provided with recesses in its sides, a gyratory crusher member 105 extending into the concave portion, a concave crushing member extending around the crusher head and having outwardly projecting lugs which extend into the recesses, said lugs having openings which are in register 110 with the openings of the frame, pieces of yielding material interposed between the lugs and the lower surfaces of the recessed portions of the frame, bolts extending through the openings of the lugs and the recessed 115 portions of the inner frame, and a binding metal interposed in a fluid state between the concave member and the concave portion of the inner frame.

6. A crusher, comprising a frame having 120 a concave portion provided with recesses in its sides which have openings extending therethrough, a gyratory crusher head extending into the concave portion, a concave crushing member extending around the crusher head and having outwardly projecting lugs which extend into the recesses, said lugs having openings which are in register with the openings of the frame, pieces of yielding material interposed between the lugs 125 130

and the lower surfaces of the recessed portions of the frame, bolts extending through the openings of the lugs and the recessed portions and through the interposed pieces of material for attaching the concave member to the concave portion of the supporting frame, and a binding metal interposed in a fluid state between the concave member and the concave portion of the inner frame.

7. In a crusher, a frame, a concave supported by said frame and having recesses in its side portions and openings communicating with said recesses, a gyratory crusher head extending into said concave, a concave liner interposed between said head and said concave and having direct engagement with the lower portion of said concave, said liner having outwardly projecting lugs extending into said recesses, bolts passing through said openings and said lugs for firmly holding said liner within said concave, and filler metal interposed between said liner and said concave and between said lugs and the walls of said recesses, said metal providing a backing for said liner against said concave remote from said direct engagement for relieving said holding bolts from rotary strain.

In testimony whereof, I affix my signature.
HARVEY H. RUMPEL.
